GUARD CABLE SPACER BRACKET

William H. Cantwell, Brandywine Hills, Del., assignor to
The Eastern Malleable Iron Company, Naugatuck,
Conn., a corporation of Connecticut

Application July 28, 1954, Serial No. 31,643

Term of patent 14 years

(Cl. D26—9)

Fig. 1.

Fig. 2.

Fig. 1 is a front perspective view of a guard cable spacer bracket embodying my new design; and

Fig. 2 is a side elevational view thereof showing the side that is hidden in Fig. 1.

It will be noted that the side of the bracket shown in Fig. 2 has a different appearance than the side visible in Fig. 1.

I claim:

The ornamental design for a guard cable spacer bracket, as shown and described.
